(57) **CLAIM**

The ornamental design for a decorative toothbrush, as shown and described.

DESCRIPTION

FIG. 1 is a front perspective view of the decorative toothbrush showing my new design, in which a brush head containment wrapper is shown in broken lines, the wrapper being environmental subject matter and forming no part of the claimed design.

FIG. 2 is a left side elevational view thereof.

FIG. 3 is a rear elevational view thereof.

FIG. 4 is a top plan view thereof.

FIG. 5 is a bottom plan view thereof; and,

FIG. 6 is a right side elevational view thereof.
